UNITED STATES PATENT OFFICE.

SAMUEL LANES, OF BROOKLYN, NEW YORK.

FOLDING BED.

1,071,441.

Specification of Letters Patent. Patented Aug. 26, 1913.

Application filed January 22, 1913. Serial No. 743,492.

To all whom it may concern:

Be it known that I, SAMUEL LANES, citizen of the United States, residing at 288 South Fourth street, Brooklyn, State of New York, have invented certain new and useful Improvements in Folding Beds; and I do declare the following to be a full, clear, and exact description of the invention, such as will enable others skilled in the art to 10 which it appertains to make and use the same.

This invention relates to beds, and more especially to folding bedsteads; and the object of the same is to make a bedstead with 15 a clothes box which is moved to opened and closed positions as the bed is opened and closed. This object is carried out by the construction set forth below and shown in the drawings, wherein—

20 Figure 1 is a plan view; and Fig. 2 an elevation.

While I do not wish to be limited to the materials of which the parts of this device are made, I prefer angle-iron where possible, with straps, rods or tubes for the braces and rungs; and the frames of the two sections or parts will each have its proper bottom as of wire spring or wire fabric, and over these springs cushions or mattresses 30 will be placed as usual. These features, the casters at the lower ends of the legs, and other details of similar character need not be described.

The framework of this bedstead is composed of two sections, whereof the main section 1 has cross rails 2 and 3 and end rails 4 and 5 of angle-iron, and angle-iron legs 6 depend from its corners, preferably having casters 7 at their lower ends, are connected 40 in pairs by longitudinal rungs 8 which may be straps and other rungs 9 of angle-iron, which latter rungs may be braced as at 10, and the end legs are connected by angle-iron rungs 11, each carrying a roller 12 near 45 its front end. The structure thus built up is strengthened by oblique braces or brackets 13 and 14 in the corners so that it shall have the proper rigidity. The second section is composed of two end bars 20 of 50 angle-iron, connected at their front extremities by a rung 21 which may be a piece of pipe flattened at its ends as seen in Fig. 1, and the bars preferably have handles 22 opposite said rung; and two upright legs 23 55 pivoted at 24 to said end bars and extending

above the same as shown. The peculiar connection between these two sections forms part of my invention. As it is in duplicate, I will describe the structure at one end of the bed only. The sections are pivotally connected by a plate 30 which rises from the end bar of the main section at its front end, a plate 31 which rises from the end bar of the second section and projects beyond its rear end so as to overlap the 60 plate 30, and a pivot 32 between these plates; and the upper end of the leg 23 is connected with the plate 30 by a link 33 pivoted at its rear end at 34 to plate 30 and at its front end at 35 to the leg. Each end bar of the 70 main section carries a support 36. When now the operator grasps the front edge of the second section and raises it, it swings around the two pivots 32 until it rests on the support, and meanwhile the swinging of 75 the links 33 around their pivots 34 which are farther to the rear than the pivots 32 causes them to fold the legs 23 into alignment with and against the end bars of the frame of the movable section just at the time that the lat- 80 ter drops onto the support 36. The width of this structure is thus reduced by half so that it becomes a couch. In connection with this structure I provide a clothes box 40 movably mounted in the framework of the 85 main section with its ends traveling over the rollers 12 thereof and its rear corners having rollers 42 which themselves move on the horizontal leaves of the angle-iron rungs 11. Without further mechanism such box 90 could be drawn out or pushed inward like an ordinary drawer, but I connect it with the links 33 so that when the bed is closed the box will be housed within the main section but when the bed is half way open the 95 box will be drawn out sufficiently to expose at least its front end when the cover 41 (with which its front half is provided as indicated in Fig. 1) may be raised. In order to effect this movement I secure castings or 100 brackets 43 to the ends of the box and employ links 44 pivotally connected at their lower ends at 45 to said brackets, and their upper ends pivotally connected as at 46 to the swinging links 33. When now the bed is folded from the position shown in Fig. 2, the pivoted points 46 describe half a circle around the pivots 34, with the result that the links 44 cause the box 40 to travel to the 105 rear in a manner which will be clear. 110

I do not wish to be limited to the materials or proportions of parts nor to the exact details of construction.

What is claimed as new is:

- 5 In a folding bed, the combination with a main section, of angle-iron rungs connecting these legs in pairs at the ends of this section, a second section hingedly connected with the front edge of the first section, and legs for
- 10 the second section pivoted thereto near their upper ends and near its front edge; of a clothes box movably mounted on said rungs,

links pivotally connecting the upper ends of said legs with the hinge elements in the main section, and other links pivotally connecting said box with the first links at points in the latter forward of their pivots to said hinge sections, for the purpose set forth. 15

SAMUEL LANES.
